PLATE LIFTING CLAMP

Edward Merrill Gardner, Brooklyn, N. Y., assignor to Merrill Brothers, New York, N. Y., a corporation of New York

Application April 14, 1945, Serial No. 588,363

6 Claims. (Cl. 294—104)

This invention relates to a new and improved plate lifting clamp having a shackle of new and improved design. The plate lifting clamp is utilizable for lifting steel plates, structural elements presenting a thin lifting edge, and other members, such as steel containers or barrels, which may have a relatively thin edge for the reception of a lifting clamp.

More particularly, my invention relates to a new and improved plate lifting clamp, operable by a vertically applied lifting force, which is especially adapted for lifting sheet metal plates and similar thin-edged metallic members from either a horizontal or vertical position, and, in fact, from any position intermediate between horizontal and vertical in which the plates or elements happen to be positioned. It is also especially useful for pulling out a horizontal plate from under a pile of plates by tilting the entire pile above the plate being extracted. It is especially suitable for use in lowering plates into the holds of ships, the working parts being protected from contact with hatch coamings or other obstructions. It is compact, light weight for its capacity, and rugged in construction, positive and instantaneous in its gripping action, and so designed that the greater the load to be lifted, the firmer is the grip by which the load is retained in the clamp. Also it will not release its grip if by inadvertence the lifting pressure is relaxed.

In manufacturing and materials-handling operations, in the construction of structural steel structures, and in many storage and assembly operations, it is frequently necessary to lift relatively heavy sheet metal plates and transport them to a new position or location. Steel plates are frequently stored in racks, either on their edges (vertically), or in piles, with the plates lying flat in a horizontal position. While plate lifting clamps are now available, and have been used for lifting relatively thin-edged structural elements or metallic containers, there has not been heretofore available a satisfactory lifting clamp of simple compact design, rugged construction, positive and instantaneous in its lifting action, which would lift thin-edged members by means of a pull or tension applied to the end of the lifting clamp regardless of whether the elements to be lifted are stacked in a horizontal or vertical position, or buried under a pile of other plates. Some of the lifting clamps now available are especially adapted for lifting plates which may be stored in the horizontal position, as when stacked one on top of the other in piles, by means of a vertical pull applied to the end of the shackle

of the clamp. Other plate lifting clamps are especially adapted for lifting thin-edged members from a vertical position, as, for example, lifting plates which are supported on their edges. While some clamps now available will lift from both horizontal and vertical positions, they do not have the simplicity of mechanical movement, nor do they supply the powerful lifting moment when lifting plates from a horizontal position, characteristic of my new and improved lifting clamp. There has not previously been available a compact, rugged, relatively light weight, positive-acting plate lifting clamp of this type, characterized by simple, smooth mechanical movements, which will function to lift plates or similar thin-edged elements from both the horizontal and vertical positions, and, in fact, from any position therebetween, by means of a lifting force or tension applied to the clamp shackle.

It is one of the objects of this invention to provide a lifting clamp embodying a shackle of a new and novel design, which clamp will function both to lift plates from a horizontal position wherein they are stacked on top of one another, and from a vertical position in which the plates may be supported on their edges, by means of a lifting force applied vertically at the end of the shackle.

Another object of this invention is to provide a clamp of this type suitable for lifting plates and similar thin-edged elements from both horizontal and vertical positions, and from any angular position therebetween in which the elements are stacked or positioned, by means of a vertical lifting force applied at the end of the clamp shackle.

A further object of this invention is to provide a lifting clamp of the type described which will be of relatively simple construction, having few operating parts, and of simple mechanical motions, thereby having but little tendency to get out of order or to require adjustment. Additional objects include providing a lifting clamp of compact and rugged, yet relatively light, construction, which is so designed that the gripping force is instantaneous and positive, and of a type such that the heavier is the load to be lifted, the firmer is the grip. It is also an object to provide a lifting clamp so designed as to insure safety, so that if the plate inadvertently rests upon some object or rests upon the floor the grip will not be released, but will hold firmly until manually released by breaking apart the interlocked plate serrations between the stationary jaw teeth and the rotating cam teeth. These objects of my invention, as well as others, will be apparent from

the ensuing detailed description of a preferred clamp construction incorporating the novel construction.

The invention may best be described with reference to the annexed drawing, wherein Fig. 1 is an elevational view of a plate lifting clamp embodying my improved shackle, the clamp being illustrated in the position it assumes when steel plates stacked vertically, as on their edges, are lifted by means of a vertical pull or lifting force applied at the end of the shackle.

Fig. 2 is a view in elevation of the improved plate lifting clamp of Fig. 1, this clamp being shown in the position it assumes when steel plates stacked horizontally, as one on top of the other, are lifted by means of a vertical lifting force applied to the clamp; and

Fig. 3 is a cross-sectional view through the clamp taken on the line 3-3 of Fig. 1.

Referring more particularly to the drawing, the operating elements comprising my invention may be enclosed in a casing or housing 4, which is preferably made of forged and tempered steel. The casing 4 includes side members 5 and 6 which are cut away to provide a slotted portion 7 to receive the plate 9 or other thin-edged element to be lifted. As shown in Figs. 1 and 3, there are provided in the slotted portion 7 of the casing 4 one or more serrated tempered gripping pads 10, forming an abutment portion of the casing, against which the plate is pressed and securely held during the lifting operation. These gripping pads may be formed integrally with the casing 4. The serrations form a gripping surface and aid in preventing the plate 9 from slipping during the gripping and lifting operation, and, since they are stationary, form a positive lock with serrations on cam 14 to prevent too easy release.

Headed pivot pins or bolts 11 and 12 serve as bearings for the operating elements described below. These pivot pins or bolts may extend entirely through the casing, and may be retained by cotter pins (not shown), in holes 11a and 12a at one end of the pins or bolts. They may also be retained in the casing 4 in some other manner, such as by upsetting the ends of the bolts.

The pivot pins or bolts 11 and 12 serve, respectively, as axes of rotation for cam 14 and radius link 15, which are positioned within the casing 4. Connecting links 17 are also positioned within the casing 4, between cam 14 and radius link 15, being pivoted at 19 to the cam 14 and at 21 to one end of the radius link 15. The other end of the radius link 15 is pivoted at 23 to one end of the shackle 24, part of which extends outside of the casing 4, and an intermediate part of which is provided with a projection 25 having the function described below. The projecting end of the shackle 24 may be provided with an aperture 26, through which may be passed lifting hook 28, at the end of which a vertical lifting force may be applied in the direction shown by the arrow through suitable means not shown. For example, a cable may be attached to hook 28 and may supply the necessary lifting force by a crane or a block and tackle arrangement not shown.

It should be noted, of course, that the shackle 24 may be constructed in various other ways and may comprise, for example, a U-shaped member providing a bight at its projecting end through which the hook 28 may be passed.

Figure 1 illustrates the situation wherein the plates to be lifted are stacked vertically, as on their edges. It is evident that when a vertical pull is applied to the shackle 24, the radius link

15 tends to rotate around its pivot 12, thereby forcing connecting links 17 downwardly and causing the cam 14 to rotate around the pivot 11 in a clockwise direction. The cam 14 is so shaped that, upon its rotation in the clockwise direction, the plate 9 is pressed tightly and securely held between the gripping teeth or serrations 14a of the cam 14 and the gripping pads 10 in the slot 7. The gripping edges 14a of cam 14 may be provided with serrations, as shown, to prevent slipping. It is evident that the heavier the load, and therefore the greater the force required to lift it applied to shackle 24, the firmer is the grip on the steel plate, and the more securely is it retained between the cam 14 and the serrated gripping pads 10. Moreover, the gripping force is applied instantaneously and positively, immediately upon application of lifting force at the end of the shackle 24.

In the view shown in Fig. 2, plates which are stacked horizontally, as one on top of the other, are lifted by means of a vertical lifting pull applied at the end of shackle 24. This view illustrates the utility of my improved lifting clamp for lifting, not only metal plates and similar thin-edged articles which are on edge, i. e., arranged vertically, but also for lifting thin-edged articles which may be arranged horizontally by means of the identical vertical pull applied to the end of the shackle 24. The projection or projecting portion 25 of the shackle 24 presses against the radius link 15, as shown in Fig. 2, when a pull is applied at the free end of the shackle. This results in forcing the upper end of radius link 15 to the right in Fig. 2, this member rotating around its pivot 12. As a result the connecting links 17 are forced to the right in Fig. 2, thereby rotating cam 14 in a counterclockwise direction around its pivot 11, since the connecting links 17 are pivoted to the cam 14, at the pivot pin 19. The plate 9 is accordingly securely held in the slot 7 of the casing 4 between the gripping pads 10 and the gripping surfaces 14a of the cam 14. As increased pull is applied to the end of the shackle 24, it is evident that the plate 9 is held all the more securely in the slot 7, the gripping force being instantaneous and positive, and the heavier the load to be lifted, the firmer is the grip. In this way the plate 9, or any other thin-edged element, may be readily lifted from the horizontal position and transferred to a new position by means of a vertical pull at the end of the shackle.

It is also evident that should plates or other thin-edged articles be stacked in any position intermediate between the horizontal and vertical, my improved lifting clamp will function in the same way. The plates are securely retained in the slot 7 and with increased pull are all the more firmly retained therein between gripping surfaces 14a of the cam 14 and the gripping pads 10 secured to the casing 4. It is thus possible to transfer such thin-edged elements to a new location by means of the vertical pull or tension applied at the end of the shackle 24 by means of a cable, rope, or otherwise.

Even when lifting horizontal plates the pressure transmitted by lug 25 causes serrations to form on both sides of the plate being lifted. Therefore, with the stationary jaw on one side the cam, as shown in Fig. 2, cannot be rotated clockwise to loosen the grip without breaking the serrations in the plate on either the cam side or the jaw side. To loosen the grip requires

manual action, and the plate is securely held until it is released by a hammer blow on the end of the shackle 24.

In the foregoing description, while I have referred to lifting plates which are stacked in vertical or horizontal positions, as illustrative of my invention, it is obvious that any other thin-edged elements may be similarly lifted. It is also apparent that the lifting clamp is of very light and compact, yet rugged construction, and is capable of applying the gripping force instantaneously and positively to the member to be lifted. It is capable of handling material of any thickness, such as plates ranging in size from the thickness of thin sheets up to the thickness of thick armor plate. The gripping force applied to the thin-edged article between the cam 14 and the casing 4, or between the gripping surfaces 14a of the cam 14 and the gripping pads 10 attached to and forming a part of the casing 4, is all the greater as the pull applied to the end of the shackle 24 is increased. The heavier the load to be lifted, the firmer is the thin-edged article held in the slot 7 of the casing 4.

While I have described one preferred embodiment of my invention, it is evident that variations and modifications therein will be readily suggested to those skilled in the art. It is, accordingly, my intention that such variations and modifications, to the extent that they are within the scope of the appended claims, shall be considered a part of my invention.

I claim:

1. A lifting clamp capable of securely retaining thin-edged elements during a lifting operation wherein said elements are lifted from either a horizontal or vertical position, said clamp comprising: a supporting member provided with a gripping surface; a pivotally mounted cam secured in spaced relationship with said gripping surface, and adapted to coact with said gripping surface during a lifting operation, said cam being so shaped that, upon rotation thereof, said element to be lifted is securely retained between said cam and said gripping surface; a pivotally mounted radius link; a connecting link secured in pivotal relationship, at each end thereof, with said cam and said radius link; and a shackle pivotally attached to said radius link said shackle being provided with a projection which abuts against said radius link when horizontally positioned thin-edged elements are to be lifted, thereby causing said radius link and said cam to rotate, whereby a thin-edged element is securely retained between said cam and said gripping surface when a lifting force is applied to said shackle.

2. A lifting clamp capable of securely retaining thin-edged elements during a lifting operation wherein said elements are lifted from either a horizontal or vertical position, said clamp comprising: a casing provided with a slotted portion for the reception of a thin-edged element to be lifted; a pivotally mounted rotatable cam having a portion thereof projecting into said slotted portion of said casing; a rotatable radius link mounted for rotation within said casing; a connecting link pivotally connected at each end thereof with said cam and said radius link; and a shackle pivotally attached to said radius link and projecting outside of said casing, said shackle being provided with a portion thereof which abuts against said radius link when horizontally positioned thin-edged elements are to be lifted, thereby causing said radius link and said cam to rotate, whereby a thin-edged element is securely

retained in said slotted portion of said casing when a lifting force is applied to said shackle.

3. A lifting clamp capable of securely retaining thin-edged elements during a lifting operation wherein said elements are lifted from either a horizontal or vertical position, said clamp comprising: a casing provided with an abutment portion thereof against which a thin-edged element to be lifted abuts during the lifting operation; a pivotally mounted rotatable cam having a portion thereof coacting with said abutment portion of said casing during a lifting operation to grip said thin-edged element to be lifted; a rotatable radius link mounted for rotation within said casing; a connecting link pivotally connected at each end thereof with said cam and said radius link; and a shackle pivotally attached to said radius link, said shackle being provided with a portion thereof which abuts against said radius link when horizontally positioned thin-edged elements are to be lifted, thereby causing said radius link and said cam to rotate, whereby a thin-edged element is securely retained between said cam and said abutment portion of said casing when a lifting force is applied to said shackle.

4. A lifting clamp capable of securely retaining thin-edged elements during a lifting operation wherein said elements are lifted from either a horizontal or vertical position, said clamp comprising: a casing provided with a slotted portion for the reception of a thin-edged element to be lifted; a plurality of pivot pins positioned within said casing; a rotatable cam having a portion thereof projecting into said slotted portion of said casing positioned within said casing, said cam being mounted for rotation on one of said pivot pins; a rotatable radius link positioned within said casing and mounted for rotation on another of said pivot pins; a connecting link pivotally connected at each end thereof with said cam and said radius link; and a shackle pivotally attached to one end of said radius link and projecting outside of said casing, said shackle being provided with a projection which abuts against said radius link when horizontally positioned thin-edged elements are to be lifted, thereby causing said radius link and said cam to rotate, whereby a thin-edged element is securely retained in said slotted portion of said casing when a lifting force is applied to said shackle.

5. A lifting clamp capable of securely retaining thin-edged elements during a lifting operation wherein said elements are lifted from either a horizontal or vertical position, said clamp comprising: a casing provided with a slotted portion for the reception of a thin-edged element to be lifted; a gripping pad secured to said casing adjacent said slotted portion; a plurality of pivot pins positioned within said casing; a rotatable cam having a portion thereof projecting into said slotted portion of said casing opposite said gripping pad, said cam being mounted for rotation on one of said pivot pins; a rotatable radius link positioned within said casing and mounted for rotation on another of said pivot pins; a connecting link pivotally connected at each end thereof with said cam and said radius link; and a shackle pivotally attached to one end of said radius link and projecting outside of said casing, said shackle being provided with a projection which abuts against said radius link when horizontally positioned thin-edged elements are to be lifted, thereby causing said radius link and said cam to rotate, whereby the thin-edged element to be lifted is securely retained in said slotted portion of said

casing between said cam and said gripping pad when a lifting force is applied to said shackle.

6. A lifting clamp capable of securely retaining thin-edged elements during a lifting operation wherein said elements are lifted from either a horizontal or vertical position, said clamp comprising: a casing provided with a slotted portion for the reception of a thin-edged element to be lifted; a gripping pad secured to said casing adjacent said slotted portion; a plurality of pivot pins positioned within said casing; a rotatable cam having a portion thereof projecting into said slotted portion of said casing opposite said gripping pad, said cam being provided with a serrated gripping portion coacting with said gripping pad to grip a thin-edged element to be lifted, and being mounted for rotation on one of said pivot

5 pins; a rotatable radius link positioned within said casing and mounted for rotation on another of said pivot pins; a connecting link pivotally connected at each end thereof with said cam and said radius link; and a shackle pivotally attached to one end of said radius link and projecting outside of said casing, said shackle being provided with a projection which abuts against said radius link when horizontally positioned thin-edged elements are to be lifted, thereby causing said radius link and said cam to rotate, whereby the thin-edged element to be lifted is securely retained in said slotted portion of said casing, between said serrated gripping portion of said cam and said gripping pad, when a lifting force is applied to said shackle.

EDWARD MERRILL GARDNER.
